CLAIM

I claim the ornamental design for a pet feeder, as shown and described.

DESCRIPTION

FIG. 1 is a perspective view of a pet feeder according to the present invention;

FIG. 2 is a front view thereof;

FIG. 3 is a rear view thereof;

FIG. 4 is a side view of the pet feeder illustrated in FIG. 1, as viewed from the left side of FIG. 2, the other side being a mirror image thereof;

FIG. 5 is a top plan view thereof; and,

FIG. 6 is a bottom view thereof.

The broken lines are for illustration purposes only and form no part of the claimed design.
